Primary Examiner — S. Bryan Reinholdt, Jr.*Assistant Examiner* — Jillian Mazzola(74) *Attorney, Agent, or Firm* — Lerner, David, Littenberg, Krumholz & Mentlik, LLP(57) **CLAIM**

The ornamental design for a belly band, as shown and described.

DESCRIPTION

FIG. 1 is a front view of a belly band according to our design;

FIG. 2 is a front bottom perspective view thereof;

FIG. 3 is a right side perspective view thereof;

FIG. 4 is a rear view thereof;

FIG. 5 is a left side perspective view thereof; and,

FIG. 6 is a front top perspective view thereof.

The broken lines shown in the drawings represent stitching lines that form no part of the claimed design.

1 Claim, 6 Drawing Sheets(56)
